CLAIM

The ornamental design for an orthotic foot brace, as shown and described.

DESCRIPTION

FIG. 1 is a perspective view of an orthotic foot brace showing our new design;

FIG. 2 is a left side elevation view thereof;

FIG. 3 is a right side elevation view thereof;

FIG. 4 is a front elevation view thereof;

FIG. 5 is a back elevation view thereof;

FIG. 6 is top plan view thereof; and,

FIG. 7 is a bottom view thereof.

The dashed lines are for the purpose of illustrating portions of an orthotic foot brace that form no part of the claimed design.
